[57] CLAIM

The ornamental design for a garment hanger, as shown and described.

DESCRIPTION

FIG. 1 is a perspective view.

FIG. 2 is a front elevational view.

FIG. 3 is a right side elevational view.

FIG. 4 is a left side elevational view.

FIG. 5 is a top plan view.

FIG. 6 is a bottom plan view.

FIG. 7 is a rear elevational view; and,

FIG. 8 is a front elevational view of a second embodiment of the design of FIG. 1, the only difference being the addition of a horizontal support which has the same configuration as the other elements of the garment hanger.

FIGS. 2-7 are shown on an enlarged scale.
